UNITED STATES PATENT OFFICE.

JOSEPH LOUIS DOSTAL, OF DETROIT, MICHIGAN, ASSIGNOR TO EARL HOLLEY, OF DETROIT, MICHIGAN.

AUTOMATIC APPLICATION OF LAMPBLACK TO METAL MOLDS.

Application filed September 27, 1922. Serial No. 590,913.

To all whom it may concern:

Be it known that I, JOSEPH LOUIS DOSTAL, a citizen of the United States, residing at 8530 Dexter Ave., Detroit, in the county of

5 Wayne and State of Michigan, have invented certain new and useful Improvements in the Automatic Application of Lampblack to Metal Molds, of which the following is a specification.

10 The object of this invention is to provide means for applying automatically a comparatively thick coating of lamp black so that the surfaces of the metal molds are well protected with lamp black.

15 In carrying out the process described in the co-pending application, Serial No. 579,927, filed August 5, 1922, by Daniel H. Meloche, it has been found necessary to provide more elaborate means than those 20 shown in my co-pending application, Serial No. 568,405, filed June 15, 1922.

The specific problem to be solved was the application of lamp black to a series of molds rotated in a horizontal plane. In 25 order to get the requisite thick coating as set forth in the application, Serial No. 579,927, referred to above I have found it necessary that the burner which produces the lamp black should be arranged to travel 30 with the molds during a portion of their travel and then by means of an escapement the burner is quickly and automatically returned to its original position where it is picked up by the next succeeding molds and 35 the operation repeated.

In the device shown in the application, Serial No. 568,405, referred to above the burner is stationary and the carbon is only deposited during the period that the mold 40 is passing the burner. With that device it was necessary to automatically open and shut the burner in order that the consumption of gas should be economized. Owing to the fact that with the device which has 45 now been developed the burner remains opposite the molds for the major portion of the time it is no longer necessary to provide means for opening and closing the gas valve, the flame being permitted to burn continuously.

Figure I is a plan view of the above machine showing the location of the mechanism in relation to the molds.

50 Fig. II is an elevation of the mechanism as viewed from the center of the machine.

Figure III is a section, at right angles to the mechanism, showing the end view of the mechanism and also showing two of the molds.

Figure IV is a section through the burner. 60

Figure V shows a cross sectional elevation on the plane 5—5 of Figure II.

Figure I shows three pairs of molds K. The curved track A supports a carriage from which a burner is suspended. B is an undulating track the purpose of which will be described later. Stationary supports W support the track A and the undulating track or guide B. The carriage supported by the four rollers C is shown travelling 70 with the molds K.

In Figures II and III AA are the rails or track which are inclined as shown in Figure II. The carriage is shown riding on the rails and travelling back after being 75 released from one mold. This carriage is provided with wheels which ride on the upper portion of the rails AA. These wheels are lettered C and the four lower wheels are lettered D. U is one of two side rollers provided to reduce the friction on the device (see also Figure I). The mechanism is thus held in all directions to the track or rails 80 AA.

E is a roller which runs on the undulating guide track B. This roller E is connected through the arm F and the shaft G to the carriage. The shaft G rotates in the bearings H. This shaft G provides a support for the tube O which in its turn supports 85 the burner block P and the burners R. I is a bar rigidly connected with the frame S of the carriage. This bar I engages with the conical plug J which projects from the mold K. L is a flexible hose connection 90 which allows gas to enter the hollow rod or tube N and so reach the burner block P and the burners R through the tube O.

M is the pivot block to which are connected the inlet tube N and the outlet tube O 100 and which in its turn is connected to the rod G so that the tubes O and N oscillate with the rod G. X is the central passage in the burner block P. T are the branch connections leading to the burners R. 105

Operation.—Assuming that the machinery is in operation and the gas flowing through the pipe L and the tube N and the tube O to the burner block P, where the gas is burning as it issues from the burners R, the 110

burner block P is carried with the moving molds K by reason of the projection J engaging with the arm I and thus moving the carriage with the molds K, the molds being 5 automatically opened at this point to permit the burner block P to swing freely between the open molds.

As the molds K carry the carriage and the burner block P forward with them the roller 10 E engages with the undulating track B causing the burner block P to swing across the face of the mold K and thus give a substantially uniform and thick coating of lamp black to the surfaces of the molds. 15 Owing to the fact that the rails AA are inclined at a distinct angle (9°) the movement of the carriage raises the burner block P and also the bar I so that ultimately the bar I no longer engages with the projecting 20 plug J, whereupon the weight of the burner R and carriage D causes the whole mechanism to run down the inclined track A at the bottom of which it remains until it is picked up by the next succeeding mold 25 and projection J, which in its turn engages with the arm I and again carries the burner with it, so that the burner is adapted to travel for a certain distance with each mold in succession and therefore, although the 30 burner is continuously in operation, for the major portion of the time it is usefully employed in coating the molds with lamp-black, thereby avoiding the necessity of alternatively opening and closing the valve 35 controlling the gas which furnishes the lamp-black.

The burner block P is provided with a central passage X leading to the bottom of the burner and the upwardly extending 40 passages T which are connected to the burners R. By this means it has been found possible to obtain a uniform distribution of the gas, otherwise the gas all escapes from the upper burners and never reaches the lower burners. On the other hand care must be taken that the upper burners receive at least as much gas as the lower burners as the upper portion of the 45 molds are subjected to the heat of the incoming metal flowing to the lower portion of the molds.

What I claim is:

1. In a molding machine an inclined stationary track, a series of molds arranged to 50 be automatically opened when passing be-

neath said track, a carriage rolling on said track, a burner suspended from said carriage, a peg projecting from each of said molds, an arm extending from said carriage and engaging with said projection 60 whereby the burner is carried forward with the mold, automatically released, returned and again carried forward by the next succeeding molds.

2. In a molding machine a stationary 65 track, a series of molds adapted to be automatically opened and to pass beneath said track, a carriage rolling on said track, a burner suspended from said carriage, mechanism interconnecting said molds and said carriage whereby the carriage and burner is carried forward with a pair of molds, 70 automatically released and returned and again carried forward by the next succeeding pair of molds.

3. In a molding machine a stationary 75 track, a series of molds adapted to be automatically opened and to pass beneath said track, a carriage rolling on said track, an oscillating burner suspended from said carriage, mechanism interconnecting said molds and said carriage whereby the carriage and burner is carried forward with a pair of molds, automatically released and returned and again carried forward by the 80 next succeeding pair of molds.

4. In a molding machine a stationary 85 track, a series of molds adapted to be automatically opened and to pass beneath said track, a carriage rolling on said track, an undulating track, an oscillating burner suspended from a shaft supported on bearings on said carriage, an arm connected to said shaft, a roller on the end of said arm, said roller being held in contact with said undulating 90 track whereby the burner is oscillated when the carriage is moved on the said rail.

5. In a molding machine, a moving 95 series of molds adapted to be automatically opened, a burner adapted to pass between 100 and to deposit lamp black upon said opened molds, a movable support for said burner, means connecting the support and each of said molds, whereby the burner is carried forward with each of said molds, automatically released and carried forward by the 105 next succeeding mold.

In testimony whereof I affix my signature.

JOSEPH LOUIS DOSTAL.
